UNITED STATES PATENT OFFICE

WALTER R. WAY, OF QUINCY, MASSACHUSETTS

LOCK

Application filed December 30, 1927. Serial No. 243,639.

This invention relates to improvements in locks. More especially it has to do with a concealed lock for holding a movable closure in closed position and for moving it to and from such position.

It is among the objects of this invention to provide a lock that is entirely concealed by the closure except for a small exposed portion arranged preferably flush with the outer surface of the closure so that it can not be gripped to pull the closure open.

But it is a feature of the invention that this exposed portion can be manipulated to effect positive movement of the closure to or from its closed position. When closed the lock will prevent dislodgment of the closure. Another feature of the improved lock is its adaptability to closures of varying lengths and of different thicknesses.

These objects and the features which characterize the invention are attained by providing a fixed member on the wall and a movable member on the closure (or vice versa), both members having co-operating portions entirely concealed from the outer

side of the wall and the movable member having a portion which can be manipulated from the said outer side and thereby effect the co-operative action of the concealed portions. In the preferred form the fixed member is a bracket secured to the inner surface of the wall, extending slightly across the opening. The movable member comprises a rotatable shaft suitably journaled in the closure

with its head or exposed end arranged substantially flush with the outer surface thereof.

Attached to the concealed end of this shaft is a spiral or helical deformed plate of considerably greater diameter than that of the shaft. With the closure placed in the opening in nearly closed position, the movable plate is moved in direction to cause its deformed portion to engage the fixed member and thereby draw the closure shut.

Upon movement of the movable member in the opposite direction the closure is forced outwardly from the opening sufficiently to permit it to be easily taken hold of and removed.

Illustrative applications of the principles

of my invention are shown in the accompanying drawings, in which

Figure 1 is a section, in elevation, of a wall with opening, a closure therefor and a lock embodying the present invention;

Figure 2 is an elevation of the front face of the wall with the closure locked shut;

Figure 3 is an elevation of the rear face of the same;

Figure 4 is a plan view of Figure 2;

Figure 5 is a plan view of the deformed plate of Figures 1, 3 and 4;

Figure 6 is an elevation, in section as on line 6—6 of Figure 2, showing the deformed plate about to engage the fixed member, or keeper, to urge the closure out of the wall opening;

Figures 7 and 8 are front elevations of different types of shaft heads;

Figures 7A and 8A are elevations of keys adapted to fit the heads of Figures 7 and 8 respectively;

Figure 9 is a perspective, partly in section, showing a modified form of shaft and cam plate;

Figure 9A is a front elevation of the head of shaft of Figure 9;

Figure 10 is a section, as on line 10—10 of Figure 9, through the modification shown in the latter figure;

Figure 11 is an elevation of a portion of a wall and closure illustrating how the lock of the invention may be disguised as a part of a design;

Figure 12 is a section as on line 12—12 of Figure 11; and

Figure 13 is an enlarged front view of the exposed end of the operating shaft of the lock of Figure 11.

Referring to the drawings the wall 1 has an opening 2 therein and a closure 3 therefor whose outer surface is to be flush with and a continuation of the wall's outer surface. The lock comprises a fixed member 4 and a rotatable member 15, the former being preferably a bracket secured to the inner face of the wall and having a portion extending from the edge of the wall part way across the opening. The rotatable member 15 comprises a shaft 6 having a cylindrical portion

6a, of less diameter than the head 6b, extending through the closure and a threaded portion 6c beyond, having one or more flat sides 6d to receive lock nut 7.

5 Preferably three of the sides of the opening 2 are perpendicular to the face of the wall, while the upper or top sides 2A is beveled downward somewhat from the front edge. The corresponding side of the closure 10 is similarly beveled. A stop 12 is attached to the inside face of the closure at the bottom to prevent outward withdrawal, and a similar stop 13 is attached to the inner face of the wall to keep the closure from being pushed inward, or if preferred dowels 14 15 may be used instead as shown in Figures 3 and 6.

To place the closure in the opening, its 20 lower side is laid upon the lower side of the opening and its upper side swung toward the wall until the threads of the rotatable member are in position to engage the projecting portion of the fixed member. A suitable handle such as a wrench or key is then applied to the head 6b and the movable member rotated. As shown in Figure 6 this projecting portion is shaped to be engaged by a 25 helical surface of the movable member 15 as the latter is rotated, thereby to cause the closure to move inward until it rests firmly against the front edge of the bracket which acts as a stop. The handle is removed leaving the closure locked securely in place in the opening, with its front surface in alignment with the surface of the wall. To 30 remove it, the handle is again applied to the head 6b and rotated in the opposite direction. The projecting portion will then be engaged by the other helical surface of the 35 deformed plate 15, causing the closure to move outward to where it can be conveniently grasped and lifted from the opening.

When the length of the closure is predetermined, it is desirable to have the top edges 40 of the helical surfaces of 15 follow, as it were, the arc of a circle, represented by line L drawn about a center O located on the front edge of the lower side of the opening.

Referring more particularly to Figures 5 45 and 6, it may be seen that the helical surfaced deformed plate 15 can conveniently be stamped from sheet stock. It is made approximately circular, with an axial hole 15a having flat sides to engage the flat sides 6d of the shaft 6. The edge of this disk is separated from the central portion 15b nearly the whole way round to form a ring portion 15c. This is then drawn axially away from the 50 central portion thereby forming the helical cam surfaces. If necessary, the section 15d of the ring which is still integrally joined to the center portion may also be bent axially in the opposite direction to make a true helix throughout its entire length. The central portion 15b is clamped between two lock nuts

7 and 7' which can be positioned on the shaft 6a wherever necessary to accommodate the lock to the thickness of the particular closure with which it is employed. In the position illustrated, the helical surface is about to engage the projecting portion of the fixed member 4 to effect withdrawal of the closure 3 from the wall.

70 Figures 7 and 8 show shaft heads 6b having, in one case, notches 6e at opposite points on the edge adapted to receive prongs 16 of a handle 17, shown in Figure 7a. The other shaft head 6b', of Figure 8, shows an irregular slot 18 into which the key 19 of Figure 8a can be inserted. The variation in the 80 shape of this slot 18 prevents the use of a coin or any ordinary key and thus guards against the manipulation of the lock by an unauthorized individual.

85 Figure 9 discloses a modified form of lock in which the movable member comprises a cylindrical shaft 20 having a hub 21 secured thereto as by pin 22. This sleeve carries a propeller like thread 23 which is adapted to engage a wall bracket (not shown) in the same manner as previously described. The movable member of this figure is mounted in a frame which comprises a bar 24 having a sleeve 25 forming a journal for the shaft 20, and a strap 26 which also constitutes a bearing for this shaft. The axial engagement of the hub 21 with the bar 24 and strap 26 prevents longitudinal movement of the rotatable member when the bar and strap have been secured to the closure 3. The head of the shaft 90 has a single transverse slot 20a into which a handle such as a screwdriver can be introduced to effect rotation of the rotatable member.

95 100 Preferably the lock of this invention has no protuberance above the closure surface itself. If the latter is provided with a raised design for purposes of ornamentation, the head of the lock shaft lends itself readily to such a decorative scheme and can easily be 105 designed to become a part of whatever figure is desired. Figure 11 illustrates such an embodiment of the invention with the closure 3 having a raised design 27, comprising rosettes 28 and 28'. One of these rosettes (28) constitutes the exposed end of shaft 6a on which, 110 interiorly of the closure, is secured the deformed plate 15 by the lock nuts 7 and 7'. This plate coacts with the fixed member 4 to draw the closure tight upon rotation of the rosette 28 in one direction and then locks the closure tightly shut, and pushes the closure 115 away from the wall upon the rosette 28 being rotated in the reverse direction. The closing movement of the closure is arrested both by its contact with a shoulder 1a on the wall as well as by the engagement of the outside molding 29 with the wall and the engagement 120 of the closure with an inside molding 125 130 135 30.

In Figure 12 the deformed plate 15^x is somewhat similar to the plate 15 already described, but here a portion of the helix is cut away so that a passageway is provided between the helix ends 15^y and 15^z, through which the other cooperating member can pass to get from one surface of the helix to the other surface.

I claim as my invention:

- 10 1. Means for securing a closure movably in a wall opening, comprising an operating shaft adapted to be mounted in and to extend rotatably through one of the wall elements and be held against axial movement therein; an engaged member adapted to be secured on the other wall element; and an engaging member projecting from the inner part of said shaft, comprising a stiff plate of stamped sheet metal having a marginal portion set oblique to the plane of the closure and positioned with respect to the engaged member so that upon rotation of the shaft it constitutes a cam for moving the closure; there being a shaft-engaging portion of the sheet metal integral with the said marginal portion and constituting a support on the shaft for said marginal portion in its said oblique position.
- 20 2. Means for securing a closure movably in a wall opening, comprising an operating shaft, adapted to extend rotatably through one of the wall elements and be held against axial movement therein; and a stiff sheet metal plate, having a plane portion with a non-round hole strung on a non-round inner portion of the shaft, and a marginal portion supported thereby and set oblique to the plane of the closure, being thereby adapted for rotating with the shaft and constituting a cam for moving the closure; and means for securing the plate against axial movement on the shaft.
- 30 3. Means for securing a closure movably in a wall opening, comprising an operating shaft adapted to extend rotatably through one of the wall elements and be held against axial movement therein; an engaging member projecting from the inner part of said shaft; and a member adapted to be secured on the other wall element; one of said members being of stiff sheet metal stock, having a portion extending helically around its axis, and having a plane portion constituting a support for said helical portion; the said member on the shaft being positioned so that, upon rotation of the shaft, the helical portion constitutes a cam for moving the closure; there being an opening between the ends of said helical portion extending both in peripheral and in axial direction, whereby upon rotation either face of said helical portion may engage the secured member as an active cam surface.
- 40 4. Means for securing a closure movably in a wall opening, comprising an operating

shaft adapted to be mounted in the closure and to extend rotatably through the closure and be held against axial movement therein; said shaft having its exposed outer end approximately flush with the surface of the closure, and having there means for an operator to rotate it; an engaging and propelling member projecting from the inner part of said shaft; and an engaged member adapted to be secured on said wall to project part way across said opening; one of said members comprising a stiff sheet metal plate set oblique to the plane of the closure; the said propelling member on the shaft being positioned so that, upon rotation of the shaft, the oblique plate constitutes a closure-propelling cam.

Signed at Wollaston, Quincy, Mass., this 19th day of December 1927.
